UNITED STATES PATENT OFFICE.

KAREL M. WEGKAMP AND CORNELUS J. PEET, OF SPOKANE, WASHINGTON.

DESIGN FOR AN ADVERTISING-CABINET.

48,429.

Specification for Design.

Patented Jan. 4, 1916.

Application filed October 14, 1915. Serial No. 55,903. Term of patent 7 years.

To all whom it may concern:

Be it known that we, KAREL M. WEGKAMP and CORNELUS J. PEET, citizens of the United States, (first papers taken out,) residing at Spokane, in the county of Spokane, State of Washington, have invented a new, original, and ornamental Design for an Advertising-Cabinet, of which the following is a specification, reference being had to the accompanying drawing, forming a part thereof.

The figure is a perspective view of an advertising cabinet illustrating our new design.

We claim:

The ornamental design for an advertising cabinet, substantially as shown.

KAREL M. WEGKAMP.
CORNELUS J. PEET.

Witnesses:

CARL B. CRAWFORD,
E. BROYLES.
